(57) **CLAIM**

The ornamental design for a packaging, as shown and described.

DESCRIPTION

FIG. 1 is a front perspective view of a packaging showing my new design.

FIG. 2 is a rear perspective view thereof.

FIG. 3 is a right side perspective view thereof.

FIG. 4 is a left side perspective view thereof.

FIG. 5 is a front elevational view thereof.

FIG. 6 is a rear elevational view thereof.

FIG. 7 is a right side elevational view thereof.

FIG. 8 is a left side elevational view thereof.

FIG. 9 is an enlarged top plan view thereof; and,

FIG. 10 is an enlarged bottom plan view thereof.
